UNITED STATES PATENT OFFICE.

ENOCH SVENSEN, OF MINNEAPOLIS, MINNESOTA.

STORM-WINDOW FASTENER.

SPECIFICATION forming part of Letters Patent No. 589,448, dated September 7, 1897.

Application filed December 15, 1896. Serial No. 615,754. (No model.)

To all whom it may concern:

Be it known that I, ENOCH SVENSEN, a citizen of the United States, residing at Minneapolis, in the county of Hennepin and State 5 of Minnesota, have invented a new and useful Improvement in Storm-Sash or Window-Screen Fasteners, of which the following is a specification.

from, leaving its straight side *e f* of about uniform thickness. It is provided with radial **V**-shaped notches adapted to receive the **V**-shaped edge of the wing *c*. The point of divergence of these radial notches is where lines of equal length drawn from *d*, *e*, and *f* would meet, (the center of the screw-hole *b*.) This plate is secured to the sash or screen by means of screws with countersunk heads. The screw-pivot *C* adjustably secures the button *A* to the casing, a common wood-screw being adapted to the purpose.

Now it will be seen that my fastener is 55 adapted to press the sash or screen close against its seat in the window-frame by reason of the variation in thickness of the plate *B*, the wing *c* of the button *A* being adjustable to any of its radial notches according to any 60 variation in thickness of the casing and sash or of the casing and screen. It will also be seen that by the interlocking of the **V**-shaped edge of the wing *c* with the radial **V**-shaped notches of the plate *B* there is no liability of 65 my fastener getting unclasped by accident.

Having thus described my invention, what I claim as new, and desire to secure by Letters Patent, is—

In a storm-sash, or window-screen fastener, 70 the combination of a button adjustably secured to the casing, by means of a screw-pivot, said button being fashioned with a wing having a **V**-shaped edge; and a plate rigidly secured to the storm-sash, or window-screen, by 75 means of screws or otherwise, said plate being of varying thickness and fashioned with radial **V**-shaped notches adapted to interlock with the **V**-shaped edge of the said button substantially as shown and described.

ENOCH SVENSEN.
